John Saburo Iato
BY B. Singer
ATTORNEY

UNITED STATES PATENT OFFICE.

TOKUSABURO SATO, OF OSAKA, JAPAN.

COKE OVEN.

Application filed October 26, 1920. Serial No. 419,765.

To all whom it may concern:

Be it known that I, TOKUSABURO SATO, a subject of the Emperor of Japan, and a resident of No. 1061, Tamade-Machi, Nishinari-
5 Gun, Osaka, Empire of Japan, have invented a new and useful Improvement in Coke Ovens, of which the following is a specification.

This invention relates to improvements in 10 coke-ovens and means for supplying air thereto, and refers particularly to means for supplying air to coke-ovens of the type in which a supply of air is led into the oven, at a convenient point between the grate and the 15 outlet flues through a series of apertures or perforations by which the air is distributed evenly through the gases. The air is preferably initially heated by passing through flues, surrounding the oven.

20 The object of this invention is to provide a simple and improved air-supply means of this type, which is simple to manufacture, is efficient in operation, and effects a very thorough distribution of the air. The invention 25 essentially comprises a hollow air-distributing box or chamber, formed of fire-brick or like fire-resisting material, and having a series of perforations in one face communicating with the hollow interior to 30 which air, preferably under pressure, is supplied.

This air-distributing means is located at a suitable point in the oven, and causes the air supply to be evenly distributed through 35 the gaseous products of combustion to ensure the complete combustion thereof.

Suitable means are provided enabling the supply of air to be varied to control the combustion.

40 In the accompanying drawings:—

Fig. 1 is a vertical longitudinal sectional view.

Fig. 2 is a horizontal sectional view of the same.

45 With reference to the figures of the drawing, the air spraying device is made of any suitable refractory material and has a plurality of staggered or honey-comb like perforations 2 in its front part, and an air chamber 3 formed in the body of the device

communicates with the atmosphere or with a supply of air under pressure.

The grouping of the perforations above referred to is one feature of this invention. The velocity of the air spray passing through 55 these perforations should be considerable on account of the very narrow passages, and in fact is so high that the air spray will cut the flame transversely instead of flowing along the line of flame, so that any gaseous 60 matter left unburnt in an oven is bound to come in contact with these high speed sprays of heated air, and the result is the complete combustion of the fuel. The amount of hot air supplied is controlled by means of a 65 regulating door fitted at the entrance of the air chamber, or other suitable means.

The efficiency of a coke oven, can be considerably increased by the use of this device.

Four of the air distributing devices are 70 shown located in the walls of the oven, chamber 16, two being located at the sides of the end wall remote from the outlet flues, and two being located in the side walls. Air is supplied through regulating valves 4, of any 75 suitable type, and passages 5 in the walls of the oven, the air being heated as it passes through these passages and being distributed from the chambers 3 through the perforations 2. 80

The perforations 2 are preferably inclined towards the outlet flues, as shown in the drawings, so that the air emerging from the perforations assists the natural draught in the oven, and the air is thoroughly distributed through and mixed with the gases generated in the chamber 16, so that the combustion of the gases is rendered complete. The burnt gases leave the chamber 16 by the flue or flues 17 and is led along 90 through the walls of the oven before reaching the discharge chamber 18. 85

What I claim is:—

A coke oven having air inlet ducts in one of its walls and also having air distributing 95 chambers on the inner side of said wall and to which the said ducts respectively lead, one of said chambers being arranged in one front corner of the oven and having a wall arranged diagonally in said corner and pro- 100

vided with rearwardly directed openings for discharging hot air rearwardly into the oven, the other air chamber being arranged in said wall near the rear end of said oven and having rearwardly and laterally inclined hot air discharge openings in its inner wall, said chamber also having an outlet flue provided with an intake toward which the

said openings of said air chambers are directed.

In testimony whereof I affix my signature in presence of two witnesses.

TOKUSABURO SATO.
